H. C. F. HAAGE

ROTARY SNOWPLOW

Filed Jan. 30, 1925

by M. Talbert Dick Atty

UNITED STATES PATENT OFFICE.

HENRY C. F. HAAGE, OF AKRON, IOWA.

ROTARY SNOWPLOW.

Application filed January 30, 1925. Serial No. 5,743.

To all whom it may concern:

Be it known that I, HENRY C. F. HAAGE, a citizen of the United States, and resident of Akron, county of Plymouth, State of Iowa, have invented a new and useful Rotary Snowplow, of which the following is a specification.

The object of this invention is to provide a simple and economical means for removing snow from streets, highways and the like.

More specifically the object of this invention is to provide a snow plow which may be secured to or removed from a tractor in a very few moments.

A further object is to provide a snow plow which will deposit the snow at the side of the road or in a truck.

A further object is to provide a snow plow which may be lowered or elevated while in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side elevation of my complete device installed on a tractor with portions of the tractor cut away to more fully illustrate the means employed to secure the shovel to the tractor.

Fig. 2 is a plan view of my snow shovel ready for installation on a tractor.

Fig. 3 is a sectional view of the power take off, taken on line 3-3 of Fig. 1.

Fig. 4 is a sectional view of the hanger means employed to secure the shovel to the front axle of the tractor and is taken on line 4-4 of Fig. 1.

I have designated the ordinary tractor by the numeral 10. The numeral 11 designates the frame of my snow plow and is of V design. This frame is designed to be secured at 12 and 13 to the axle 14 of the tractor 10 by the hangers 15. Secured to the rear end of the tractor and positioned above the rear end of the frame 11 is the bracket 16. Threaded into this bracket is the screw 17 which frictionally engages the well 18 in the end of the frame 11. Mounted on the front of this frame is the shovel 19. The numeral 20 designates an upturned flange around the side and back of the shovel

to prevent the snow from falling over the sides and back of the shovel. Secured to the front of the shovel are the runners 21, which are designed to support the shovel a certain distance from the ground. Near the rear of the shovel 19 is the opening 22 which communicates with a blower box designated by the numeral 23. The numeral 24 designates a centrifugal fan mounted in the blower box 23. The numerals 25 and 26 designate pipes which communicate with the blower box and are so positioned relative to the force of the fan 24 that the snow entering the blower box is blown through them. At each of their outlet ends is a deflector or baffle plate, which I have designated by the numerals 27 and 27'. They are pivotally mounted so that they may be adjusted to various positions. These positions may be permanently retained by tightening the thumb screws 28 and 28'. The numeral 29 designates a brace that is secured to the frame and the pipes 25 and 26. Securely attached to the fan shaft 30 is the bevel gear 31, which is shown in Fig. 2. The numeral 32 designates a shaft journaled in the bearing 33. At one end it has permanently secured thereto the bevel gear 34 which engages the first mentioned bevel gear 31. Secured to the other end of the shaft 32 is another bevel gear which is designated by the numeral 35 which engages the bevel gear 36 secured to the second shaft 37. This shaft 37 is journaled in the housing 38 which is designed to be bolted to the tractor and over the power take off by the studs 39 and 40. Secured to this shaft and within the housing 38 is the bevel gear 41 which engages the bevel gear 42. This bevel gear 42 is mounted on the power shaft of the tractor 10. I have designated this shaft by the numeral 43 and the bearing in which it is journaled by the numeral 45.

The practical operation of this invention is as follows:

Place the complete device beneath a tractor. Secure the hangers 15 to the axle 12 and screw the member 17 down until it engages the well 18 in the frame 11. Connect the fan driving mechanism to the power take off and the shovel is ready for use. It will readily be noted that if the member 17 is screwed up or down the front end of the shovel will be lowered or elevated, the necessity of which will be readily understood. As the fan mechanism is in engagement with

the power take off of the tractor the fan will be in operation as soon as the motor is started. As the tractor moves forward the snow is forced upon the shovel 19 and as there is a suction at the opening 22 the snow will be drawn through this opening into the blower box and from here will be forced through the pipes 25 and 26 and deposited at the side of the road. The position of depositing this snow along the road may be regulated by the deflector plates 27 and 27'. If it is desired the pipes 25 and 26 may be elevated to such a position that the snow may be deposited into a truck. To remove my attachment from the tractor, merely detach the fan driving mechanism from the power take off and detach the hangers 15 from the front axle.

Having fully described my invention, what I claim and desire to obtain by Letters Patent, is:

1. In a device of the class described, a snow shovel having an opening, a blower box below said opening and communicating with said opening, flanges on the sides of said shovel converging rearwardly so that the snow is directed into said opening, a centrifugal fan mounted within said blower box, means for rotating said fan, and outlet pipes communicating with said blower box, for the purposes stated.

2. In a device of the class described, a snow shovel having an opening, a blower box below said opening and communicating with said opening, flanges on the sides of said shovel converging rearwardly so that the snow is directed into said opening, a centrifugal fan mounted within said box, pipes leading from said box, deflector plates at the ends of said pipes, and means for rotating said fan, for the purposes stated.

3. In combination with a tractor having a power take off, a rotary snow plow, comprising a shovel having an opening, a blower box communicating with said opening, flanges on the sides of said shovel converging rearwardly so that the snow is directed into said opening, a centrifugal fan mounted within said box, a pipe leading from said box, and means for operatively connecting the power take off of said tractor to rotate said fan, for the purposes stated.

4. In combination with a tractor, a rotary

snow plow, comprising a shovel having an opening, a blower box communicating with said opening, flanges on the sides of said shovel converging rearwardly so that the snow is directed into said opening, a centrifugal fan mounted within said box, pipes leading from said box, adjustable deflector plates at the end of said pipes, and means for rotating said fan by the engine of said tractor.

5. In combination with a tractor having a power take off, a rotary snow plow comprising a frame, a shovel mounted on said frame, said shovel having an opening, a blower box communicating with said opening, flanges on the sides of said shovel converging rearwardly so that the snow is directed into said opening, a centrifugal fan mounted within said box, pipes leading from said box, hangers for securing said frame to said tractor, and means for operatively connecting the power take off of said tractor with said fan.

6. In combination with a tractor, a rotary snow plow comprising a frame, a shovel mounted on said frame, said shovel having an opening, a blower box communicating with said opening, a centrifugal fan mounted within said box, a pipe leading from said box, hangers for pivotally securing said frame to the front axle of said tractor, a bracket on the rear of said tractor, and a screw threaded into said bracket and designed to engage the rear end of said frame, for the purposes stated.

7. In combination with a tractor having a power take off, a rotary snow plow comprising a frame, a shovel mounted on said frame, said shovel having an opening, a blower box communicating with said opening, flanges on the sides of said shovel converging rearwardly so that the snow is directed into said opening, a centrifugal fan mounted within said blower box, pipes leading from said box, means connected with the power take off of said tractor to rotate said fan, hangers for pivotally securing said chassis to said tractor and means for vertically adjusting said shovel, for the purposes stated.

Signed at Akron, in the county of Plymouth and State of Iowa, this 30th day of December, 1924.

HENRY C. F. HAAGE.
